UNITED STATES PATENT OFFICE.

NICHOLAS SIMON, OF NEENAH, WISCONSIN.

DESIGN FOR A CHEESE.

SPECIFICATION forming part of Design No. 34,319, dated April 2, 1901.

Application filed March 11, 1901. Serial No. 50,761. Term of patent 7 years.

To all whom it may concern:

Be it known that I, NICHOLAS SIMON, a citizen of the United States, residing at Neenah, in the county of Winnebago and State of Wisconsin, have invented and produced a new and original Design for a Cheese, of which the following is a specification, reference being had to the accompanying drawings, forming part thereof.

Figure 1 is a perspective view of the upper or top side of the cheese and two of its edges, showing my design. Fig. 2 is a perspective view of the reverse or bottom side and the other two edges, and Fig. 3 is a vertical section taken on the line *a a* of Fig. 1.

As shown in the drawings, the leading feature of my design consists of a rectangular-shaped cheese having a series of V-shaped grooves 1, which divide the cheese into small rectangular sections, said V-grooves being arranged directly opposite each other upon opposite sides of the cheese, three of them extending entirely around the cheese trans-

versely of it and one of the grooves extending entirely around the cheese longitudinally, the other two only across its ends and partially across its top and bottom surfaces. There is also a half-circle groove 2 around each of the small rectangular sections, near their outer edges, upon the top side of the cheese, which forms smaller rectangular sections or name-plates for receiving any desired inscription.

Having thus described my said invention, what I claim as new, and desire to secure by Letters Patent, is—

The design for a cheese as herein shown and described.

In testimony whereof I have signed my name in the presence of two subscribing witnesses.

NICHOLAS SIMON.
